UNITED STATES PATENT OFFICE.

JULES P. METZGER, OF CARLSTADT, NEW JERSEY, ASSIGNOR TO THE LESLIE COMPANY, OF LYNDHURST, NEW JERSEY, A CORPORATION OF NEW JERSEY.

COUPLING.

1,186,324.

Specification of Letters Patent.

Patented June 6, 1916.

Application filed July 9, 1915. Serial No. 38,860.

To all whom it may concern:

Be it known that I, JULES P. METZGER, a citizen of the United States, and a resident of Carlstadt, in the county of Bergen and 5 State of New Jersey, have invented a new and Improved Coupling, of which the following is a full, clear, and exact description.

The object of the invention is to provide a new and improved coupling more especially designed for use on the injector of a 10 locomotive and arranged to enable the engineer to quickly couple or uncouple the steam supply pipe and the injector.

In order to produce the desired result, use 15 is made of a coupling member provided with an internal retaining flange and a locking ring provided on its peripheral face with spaced annular shoulders forming a groove between them, the said flange extending into 20 the said peripheral groove and being straddled by the said shoulders, the said locking ring being made in sections, of which one is the key section. Use is also made of a manually controlled external locking device held 25 on the coupling member and engaging the key section.

A practical embodiment of the invention is represented in the accompanying drawings forming a part of this specification, in 30 which similar characters of reference indicate corresponding parts in all the views.

Figure 1 is a longitudinal central section of the coupling as applied and connecting an injector with its steam supply pipe, the 35 section being on the line 1—1 of Fig. 2; Fig. 2 is a cross section of the same on the line 2—2 of Fig. 1; Fig. 3 is a longitudinal central section of a modified form of the coupling; Fig. 4 is a similar view of another 40 modified form of the coupling; Fig. 5 is a similar view of another modified form of the coupling; Fig. 6 is a face view of a modified form of the key section of the locking ring; Fig. 7 is a plan view of the same with part 45 shown in section; Fig. 8 is a longitudinal central section of the coupling provided with a modified form of locking device for the key section of the locking ring; Fig. 9 is a cross section of the same on the line 9—9 of

Fig. 8; Fig. 10 is a longitudinal central section of the coupling provided with another modified form of locking device for the key section; Fig. 11 is a cross section of the same on the line 11—11 of Fig. 10; and Fig. 12 is a face view of the key section of the coupling 50 shown in Figs. 10 and 11.

In locomotive service the steam connections and couplings for same are of primary importance and this is particularly so in reference to the injectors and their pipe 55 connections. The present invention permits of making repairs in case of mishap to the equipment in the quickest possible time. In case of the breaking of brazed or other joints of locomotive connections, these parts 60 have to be renewed. This is accomplished with great difficulty with ordinary couplings, requiring in some cases the cutting 65 of pipe and rebraze of sleeves, frequently making it impossible to do the repairs on the 70 road and requiring the train to be taken to the round house, thus subjecting the trains to great delay.

In the present improvement, the novel construction of parts presents the best possible 75 means of disconnecting and connecting the parts, the improvement providing reversible parts, so that it is impossible to put them in wrong position, and the coupling or renewal of the coupling nut can be 80 accomplished in the shortest possible time.

In former devices of this class, some are complicated, requiring special tools, and others are difficult to get at, and the parts used have to be selected, as they are 85 right and left parts, and in such cases it is not really certain that the parts are properly assembled, or in proper alinement or that one part is not binding upon the other. This is especially the case when the work has to 90 be done not only in the quickest time, but while the parts may be hot and the repairs may have to be made at night. In the present invention the engineer can couple or uncouple by merely feeling the parts and 95 when the parts are put together a perfect joint is insured.

The coupling illustrated in Figs. 1 and 2

is shown applied to a locomotive injector for coupling the steam pipe A to the threaded part or nipple B' of the injector B. The pipe A, which is usually made of 5 copper, is provided with a coupling head A' in the form of a sleeve, soldered, brazed or otherwise fastened to the end of the pipe A, and the said coupling head is provided at its forward end with an annular shoulder 10 A² adapted to abut against the end of the nipple B', the contacting parts being preferably beveled to form a tight joint, as plainly indicated in Fig. 1. On the nipple B' screws a coupling nut C provided at its 15 outer end with an inwardly extending annular flange C' straddled by spaced annular shoulders D' and D² formed on the peripheral face of a locking ring D fitting onto the head A' of the pipe A and adapted to 20 abut against the shoulder A², as plainly indicated in Fig. 1. It is understood that the flanges D' and D² form between them a groove into which extends the flange C' so that when the nut C is screwed up on the 25 nipple B' the locking ring D firmly draws the head A' in engagement with the nipple B' to properly couple the members A and B together. The locking ring D is made in sections, preferably, a key section D³ and 30 two side sections D⁴ and D⁵, as plainly indicated in Fig. 2. By constructing the locking ring D in the manner described, the section can be readily removed from the nut C on unscrewing the latter and moving the 35 ring beyond the coupling head A' onto the pipe A. It is understood that when the nut C and the ring D reach this position they can be readily moved into eccentric position relatively to the pipe A to allow of moving 40 the key section D³ from the flange C', after which the side sections D⁴, D⁵ can also be conveniently removed from the flange C'. It will be noticed that the said sections D⁴, 45 D⁵ are interchangeably reversible and hence the engineer is enabled to quickly place the same in position after repairs are made and the pipe is again to be coupled to the injector. The key section D³ is reversible so that it can be placed quickly and conveniently in position to hold the side sections 50 D⁴, D⁵ in place and to allow of engaging the ring with the flange C'. After the parts are assembled the locking ring can be readily slipped onto the head A' and on screwing 55 up the nut C causes a re-coupling of the members A and B, as previously explained. The flange C' is provided with a bevel C² at its outer face to permit of conveniently engaging the sections D³, D⁴ and D⁵ with the 60 flange C' when assembling the parts as above explained. In order to prevent accidental dropping out of the key section D³ on uncoupling the parts, use is made of a retaining or locking device E, preferably in

the form of a spring secured to the peripheral face of the coupling nut C and engaging with its free end a slot or groove D⁶ formed on each side of the key section D³. It is understood that by this arrangement the spring E engages the groove D⁶ which 70 is outermost at the time.

In the modified form shown in Fig. 3, the pipe A is provided with an integral head A³ having a shoulder A⁴ onto which fits the ring D engaged by the flange C' of the coupling nut C screwing on the nipple B' of the injector B. Otherwise, the construction is 75 the same as above described in reference to Figs. 1 and 2.

In the modified form shown in Fig. 4, the flange C² of the coupling nut C is beveled at both the inner and outer sides and the shoulders D' and D² of the locking nut D are similarly beveled at their inner opposite sides. Otherwise the construction is similar 85 to that shown in Fig. 3.

In the modified form shown in Fig. 5, the locking ring D has its inner wall rounded off. Otherwise the structure is practically the same as above described in reference to Figs. 1, 2, 3 and 4.

The groove D⁶ of the key section D³ instead of being straight as shown in Fig. 2, may be curved, as indicated in Figs. 6 and 7, and the back wall of the groove is preferably 95 slightly indented as at D⁷ for engagement by the free end of the spring E to prevent shifting of the locking ring D on the head A' of the pipe A.

The locking device E, shown in Figs. 8 100 and 9, consists of a spring attached to the coupling nut C, and on the free end of the spring is secured a dovetailed tongue E' adapted to engage a correspondingly shaped groove D⁸ formed in key section D³ of the 105 locking ring D. It is understood that the dovetailed groove D⁸ is on both sides of the key section D³ to allow of placing the latter in either position on the head A' of the pipe A.

In the modified form of the locking device shown in Figs. 10 and 11, the key section D³ is provided on each side with a groove D⁸, the same as above described in reference to 115 Figs. 8 and 9, and either groove is engaged by a correspondingly shaped block E² held on a rod E³ attached to the coupling nut C. The block E² is provided with finger pieces E⁴ adapted to be taken hold of by the engineer to permit of conveniently moving the block E² out of engagement with the dovetail groove D⁸ whenever it is desired to uncouple the coupling. A spring E⁵ is coiled 120 on the rod E³ and presses the block E² so as to hold the latter normally in engagement with the groove D⁸.

From the foregoing it will be seen that the coupling shown and described is very

- simple in construction and its parts can be readily assembled and applied to the members to be coupled together. It will also be noticed that by making the locking ring in 5 sections, of which the side sections are interchangeable and reversible and the key section is reversible, the engineer does not experience any difficulty in assembling the parts in daylight or during the night.
- 10 I do not limit myself to the particular application of the coupling as shown and described, as it is evident that the coupling may be used for coupling other members than those shown and described.
- 15 Having thus described my invention, I claim as new and desire to secure by Letters Patent:
1. A coupling, comprising a coupling member provided with an internal retaining flange, a locking ring provided on its peripheral face with spaced annular shoulders forming a groove between them, the said flange extending into the said peripheral groove and being straddled by the said 20 shoulders, the said locking ring being made in sections of which one is the key section, and locking means for the key section.
2. A coupling, comprising a coupling member provided with an internal retaining flange, a locking ring provided on its peripheral face with spaced annular shoulders forming a groove between them, the said flange extending into the said peripheral groove and being straddled by the said 25 shoulders, the said locking ring being made in sections of which one is the key section, and a locking device held on the said coupling member and engaging the said key section.
- 30 3. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 35 in sections of which one is the key section, and a locking device held on the said coupling member and engaging the said key section.
- 40 4. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 45 in sections of which one is the key section, the said key section being provided on its sides with grooves, and a locking device held on the coupling member and adapted to engage the side groove outermost at the time.
- 50 5. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 55 in sections of which one is the key section, the said key section being provided on each side with a groove, and a spring attached to the coupling member and engaging with its free end the said side groove outermost at the time.
- 60 6. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 65 in sections of which one is the key section, the said locking ring sections being reversible.
7. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 70 in sections of which one is the key section, and the other two are the side sections, the latter being interchangeable, the key section being reversible, and means for holding the key section in place.
8. A coupling, comprising a coupling member provided with an internal retaining flange, a locking ring provided on its peripheral face with spaced annular shoulders forming a groove between them, the said flange extending into the said peripheral groove and being straddled by the said shoulders, the said locking ring being made 75 in sections of which one is the key section, and the other two are the side sections, the latter being interchangeable, the key section being reversible, and means for holding the key section in place.
9. In a coupling, the combination of two members to be coupled together, one of the members being provided with an external thread and the other member having a coupling head smaller in diameter than the said thread, a coupling nut screwing on the said thread, and a sectional ring engaging the said nut and the said coupling head, the sections of said ring being reversible and one of the sections being a key section.
10. In a coupling ring the combination of two members to be coupled together, one of the members being provided with an external thread and the other member having a coupling head smaller in diameter than the said thread, a coupling nut screwing on the 125

said thread, a sectional ring engaging the said nut and the said coupling head, the sections of the said ring being reversible and one of the sections being a key section, and 5 a manually controlled retaining device mounted on the said nut for holding the key section in place.

In testimony whereof I have signed my name to this specification in the presence of two subscribing witnesses.

JULES P. METZGER.
